LLP

CLAIM

The ornamental design for a case for electronic device with multi-angle stand, as shown and described.

DESCRIPTION

FIG. 1 is a front perspective view of a case for electronic device with multi-angle stand shown in a first configuration of an open position;

FIG. 2 is a front elevation view thereof, in the first configuration of an open position;

FIG. 3 is a rear elevation view thereof, in the first configuration of an open position;

FIG. 4 is a right-side elevation view thereof, in the first configuration of an open position;

FIG. 5 is a left-side elevation view thereof, in the first configuration of an open position;

FIG. 6 is a top plan view thereof, in the first configuration of an open position;

FIG. 7 is a bottom plan view thereof, in the first configuration of an open position;

FIG. 8 is a rear perspective view thereof, in the first configuration of an open position;

FIG. 9 is a front perspective view thereof, shown in a second configuration of an open position with electronic device and stylus included;

FIG. 10 is a right-side elevation view thereof, in the second configuration of an open position;

FIG. 11 is a front perspective view thereof, shown in a third configuration of an open position with electronic device and stylus included;

FIG. 12 is a right-side elevation view thereof, in the third configuration of an open position; and,

FIG. 13 is a rear perspective view thereof, in a closed position.

The broken lines represent portions of the invention and an electronic device and stylus that form no part of the claim.

1 Claim, 13 Drawing Sheets
